CINDER DISPOSAL APPARATUS

Richard M. Crosby, Seattle, Wash.

Application July 11, 1930, Serial No. 467,235

3 Claims. (Cl. 110—50)

My invention relates to cinder disposal apparatus as applied to the smoke box of a steam locomotive and more particularly to a cinder disposal device which may be associated with a spark arrester for conveying the cinders deposited therein to the ash pit or fire box of the locomotive.

An object of my invention is to provide a cinder disposal device of the above character which is of durable construction and can be quickly and easily attached to any type of locomotive.

Another object of my invention is the provision of a combination neutralizer terminating within the forward end of a conveyor forming a part of the cinder disposal apparatus which, through the agency of exhaust steam, live steam or blower steam connected thereto functions during various running conditions of the locomotive to provide positive means for the disposal of cinders from the smoke box of the locomotive to the fire box of the same.

Another object of my invention is the provision of exhaust steam connections from the exhaust cavities of the locomotive cylinders to the neutralizer. This exhaust steam when the locomotive is operating passes through the neutralizer and discharges into the conveyor simultaneously with the passage of the exhaust steam through the exhaust nozzle in the smoke box to overcome any partial vacuum which may be created in that portion of the conveyor leading from the smoke box due to this exhaust nozzle discharge thus assuring a positive delivery of cinders through the conveyor to the fire box.

A further object of my invention is the provision of a live steam connection to the neutralizer in combination with the exhaust steam connections which functions to discharge steam through a combining tube forming a portion of the neutralizer into the same, to overcome any partial vacuum which may exist in that portion of the conveyor leading from the smoke box when the locomotive is working with a light throttle or running slowly.

A still further object of my invention is the provision of openings in an end plate supporting the neutralizer at the forward end of the conveyor for the admission of air around the nozzle end of the neutralizer within the conveyor to support combustion of gases and cinders passing through the same and to prevent the abrasive action of cinders on the interior wall of the conveyor.

Another object of my invention is the means for providing an injector effect produced by the dis-

charge of the live steam through the nozzle of the neutralizer to induce air through the openings in the forward end of the conveyor while the locomotive is running slowly to support combustion of the gases and cinders passing through the conveyor.

Another object of my invention is the provision of a steam blower connection to the neutralizer and discharging therein through the combining tube of the same simultaneously with the discharge of the blower steam in the exhaust nozzle in the smoke box to eliminate any partial vacuum which may exist in that portion of the conveyor leading from the smoke box and also produce an injector effect to induce air through the openings in the forward end of the conveyor while the locomotive is standing still.

The above objects of my invention as well as others not particularly pointed out above will be more fully hereinafter described and for a more complete understanding of my invention reference may be had to the accompanying drawings in which like reference characters in the several views denote like parts and in which:

Fig. 1 is a side elevation of a steam locomotive showing the cinder disposal apparatus of my invention connected thereto;

Fig. 2 is an elevation partly in section of the smoke box of a locomotive clearly showing the method of associating the cinder disposal apparatus of my invention to the same;

Fig. 3 is a plan view of Fig. 2;

Fig. 4 is an enlarged sectional view along the line 4—4 of Fig. 3 to clearly illustrate the combined neutralizer forming a portion of the cinder disposal apparatus, and

Fig. 5 is a sectional view along the line 5—5 of Fig. 4 looking in the direction of the arrows.

Referring now to Fig. 1, a steam locomotive to which my invention is applicable is shown in elevation and comprises in general the fire box A, the boiler B, the steam dome C which also contains the usual throttle valve for the admission of steam into the usual pipe lines connected to the cylinders D. The smoke box E, which also contains the exhaust nozzle N, comprises a compartment positioned forward of the boiler B and is shown equipped with a spark arrester F of the type known as a cyclone arrester and for the purpose of illustrating and describing the operation of the cinder disposal device of my invention I have shown the same applied to a smoke box thus equipped.

The cinder disposal device of my invention as illustrated in Fig. 1 is indicated generally by the

55

reference character G and comprises in general a cinder conveyor H having its one end terminating in the arrester F and its other end terminating in the fire box A of the locomotive. A 5 neutralizer J associated with the cinder conveyor H is provided with connections leading from the exhaust cavities O of the cylinders D, the steam blower line K and a branch L extending from the steam line leading to the cylinders. These steam 10 connections in combination with the neutralizer J provide means for positively conveying cinders from the arrester F through the conveyor H to the fire box A as will be hereinafter pointed out.

In Fig. 2 I have shown a substantial portion of 15 the smoke box E of the usual type positioned forward of the boiler head 2 which with the upper and lower shell plates 3 and 4 and the head or cover 5 of the locomotive form the walls of the same. The exhaust nozzle N which receives the 20 exhaust steam from the cylinders D of the locomotive terminates in the smoke box E and supports at its upper end 7 a cyclone type of arrester F, the tip 7 of the same terminating within the arrester F. This type of arrester comprises 25 a cylindrical chamber 8 provided with an intake opening 9 and an outlet in the form of a cylindrical stack 10 depending from the top plate of the arrester into the interior of the same and in turn suitably connected with the external 30 stack 12 of the locomotive.

When the locomotive is moving, exhaust steam from the exhaust steam cavities O of the cylinders D will be intermittently delivered to the exhaust nozzle N and this exhaust steam, as is well 35 understood, creates a draft in the fire box A which causes the products of combustion to enter the flues of the boiler and pass into the smoke box E. These products of combustion which include smoke, gases and cinders are thus drawn 40 into the mouth or intake opening 9 of the arrester F and pass therethrough to the external stack 12. The cinders which form a portion of these combustion products that are not discharged through the stack, drop to the bottom of 45 the arrester into a suitable pocket formed in the bottom of the same. The cinders thus deposited may be removed from the front end of the locomotive from time to time by removing the front plate or head 5 of the same.

50 The structure thus far described in itself forms no part of the present invention, except in so far as it may cooperate with the subject matter hereinafter described.

It is to this end that I have devised the cinder 55 disposal apparatus in the arrester whereby the cinders may be carried from the same to the fire box A through a suitable conveyor pipe or tube H and in combination with the neutralizer J which is connected to the exhaust steam cavities 60 O of the locomotive cylinders D, the live steam line, and steam blower line positively affect the the disposal of the cinders from the cyclone F.

Referring particularly to the conveyor pipe H through which the cinders are delivered to the 65 fire box A, it comprises an angularly disposed section of tubing 14 of suitable size, the upper end 15 of which terminates in the bottom of the arrester F, and forms the intake of the conveyor H. This angularly disposed section of tubing 14 70 extends downwardly and rearwardly at a suitable angle through the bottom of the smoke box and terminates in a horizontally disposed section of tubing 16 near the forward end of the same. This horizontal section of tubing 16 is positioned exteriorly of the locomotive immediately

under the belly of the boiler shell and is suitably supported. The section 16 extends rearwardly and terminates in the fire box A just beneath the arch therein.

The forward end 17 of the horizontal section 16 is closed by a suitable plate 18 having threaded engagement with the bore of the same and carries the neutralizer J. The neutralizer J comprises in part a tubular member 19, the exteriorly threaded end 19^a of which is threaded into a central orifice 20 in the plate 18. A nozzle 21 having its one end threaded in the bore 22 of the member 19 extends rearwardly into the horizontal section 16 and terminates at the opening 23 formed by the junction of the angularly disposed section 14 and the horizontal section 16 of the conveyor H. The member 19 is provided with a lateral branch 24 disposed at an angle of 45° and has connected thereto a pipe 25 provided with branch extensions 26 and 27 which are connected respectively to the exhaust steam cavities O of the right and left hand cylinders D of the locomotive. A portion of the exhaust steam from the exhaust cavities O when the locomotive is running will be intermittently delivered through the branch pipe extensions 26 and 27, the pipe 25 into the bore 22 of the member 19 and discharged through the nozzle 21 in the immediate vicinity of the opening 23.

In addition to the exhaust steam connections 30 from the exhaust cavities O as just described, the steam blower line K and a branch L from the steam line 30 leading to the cylinders D are also connected to the neutralizer J. The steam blower line K, which is controlled from the cab of 35 the locomotive is for the usual purpose of creating an induced draft when the locomotive is shut off or when firing up, as is well understood. The steam blower line K is tapped by a branch 31 extending from a T-fitting 32 conveniently inserted in the steam blower line K and has inserted therein a suitable check valve 33. The steam line 30 leading from the steam dome C is conveniently tapped as at the point 34 and a branch 35 extending therefrom has inserted therein a suitable check valve 36. The outlets of the respective valves 33 and 36 are connected to a pipe line 37 through the medium of a suitable T-fitting 38 which terminates in a combining tube 39 secured in the leg 40 of the 50 member 19 of the neutralizer J.

The combining tube 39 comprises a body 40^a having externally threaded portions 41 and 42 located to the left and right of an intermediate hexagonally shaped enlargement on its outer wall adapted to be received within the head of a wrench. The externally threaded portion 42 of the body 40 is received in the internally threaded end portion of the bore 22 in the member 19. The externally threaded portion 41 of the body 60 40 is adapted to receive a clamping nut 43 for securing the pipe 37 leading from the live steam and steam blower connections to the intake end of the combining tube 39. A central bore 45 through the combining tube 39 is reduced at 65 its nozzle end 46 to form a restricted opening 47 terminating within the bore 22 of the member 19 of the neutralizer J. This restricted opening 47 discharges steam from the steam blower line K or the steam line L into the bore 22 of the 70 member 19 and is for purposes as will presently be described.

Assuming that the locomotive is moving, the pistons are therefore reciprocating and exhaust steam from the exhaust cavities O of the cyl- 75

inders D will be intermittently delivered to the exhaust nozzle N in the smoke box E for creating the usual draft, as is well understood. This exhaust steam passing through the exhaust nozzle tip 7 has a tendency to create a reduced pressure or partial vacuum in the spark arrester F and the angularly disposed section 14 of the conveyor H. Simultaneously with the intermittent delivery of exhaust steam to the exhaust nozzle N, exhaust steam from these exhaust cavities O of the cylinders D will also be delivered through the pipe extensions 26 and 27 and pipe 25 and discharged through the nozzle 21 into the horizontal section 16 of the conveyor H in the vicinity of the opening 23. The effect of this exhaust steam as intermittently discharged through the nozzle 21 overcomes any reduced pressure or partial vacuum in the spark arrester and angularly disposed section 14 of the conveyor H which may be created by the exhaust steam at the nozzle N and permits the draft created in fire box A by the passage of exhaust steam through the exhaust nozzle, as is well understood, to function to assure a flow of air, steam or gases with the cinders from the smoke box E through the angularly disposed and horizontal sections of the conveyor to the fire box A into which the horizontal section terminates. The plate 18 secured in the forward end of the horizontal section 16 is provided with a plurality of orifices 50 suitably spaced therein which communicate with the interior of the horizontal section 16 to permit the induction of a predetermined amount of air which assists in the movement of the cinders through the horizontal section 16 and also furnishes oxygen for supporting the combustion of the gases and partially burned cinders and also prevents the abrasive action of the cinders on the interior wall of the horizontal section of the conveyor. Thus the effect of the exhaust steam as discharged in the neutralizer eliminates any reduced pressure or partial vacuum in the spark arrester chamber and angularly disposed section 14 of the conveyor H and the induction of air into the section 16 in combination with the suction created therein by the draft in the fire box A provides a free passage for the cinders and gases back into the fire box A.

Under normal operating or speed conditions of the locomotive, the branches 26 and 27 from the exhaust cavities O of the cylinders D to the neutralizer are sufficient to function and properly neutralize any reduced pressure in the cinder conveyor section 14 as just described. However, the live steam line 30 to the cylinders D is tapped as before described and the extension 35 leading therefrom terminates in the combining tube 39 of the neutralizer and acts to overcome any reduced pressure or partial vacuum created in the arrester F and the angular section 14 of the conveyor H between exhausts of the locomotive when the same is working with a light throttle or running slowly to insure a proper delivery of the cinders from the arrester to the fire box A. Due to the fact that the operation of a locomotive is so intermittent and changeable under varying conditions, I provide this live steam connection to insure the proper functioning of the cinder disposal apparatus under all working conditions of the locomotive. Also due to the arrangement of the nozzle end 46 of the combining tube 39 in the member 19 and its concentric position therein with relation to the nozzle 21, the steam from the live steam connection discharging through this nozzle 46 expands in the member 19 and discharges through this nozzle 21 into the horizontal conveyor section 16 at greatly reduced pressure. This discharge through the nozzle 21 thus produces an injector effect for the purpose of inducing air into the horizontal section 16 through the openings 50 to aid in the combustion of the partially burned gases and cinders and also prevent gases from the fire box A passing into the conveyor section 16 between 10 exhaust discharges when the engine is running slowly.

The steam blower line K is controlled from the cab of the locomotive and is ordinarily made use of when firing the locomotive or when the same is standing still and is connected to the exhaust nozzle N to create a vacuum in the arrester F to produce a draft in the fire box and a suction in the cinder conveyor H. The branch 31 to the combining tube 39 also discharges steam 20 through the nozzle 46 of the same which passes through the nozzle 21 and acts to overcome any reduced pressure or partial vacuum created by the steam blower in the arrester F and angular section 14 due to its discharge into the exhaust 25 nozzle N, to permit the draft created in the fire box A to function to provide a suction in the conveyor H for the proper disposal of cinders and gases from the arrester F. The steam discharging through the nozzle 46 also produces 30 an injector effect to draw air into the horizontal section 16 through the orifices 50 in the plate 18 as already referred to.

From the above description it is apparent that the steam blower which is used when the locomotive is standing still and the live steam connection as used when the locomotive is working under certain conditions perform the same functions of overcoming any reduced pressure or partial vacuum at the intake throat of the conveyor 40 H and produce an injector effect as before described. The pressures of these two lines are equal and the check valve 33 associated with the steam blower extension is open to steam from the steam blower line and closed to the steam 45 line. The check valve 36 associated with the branch steam line is open to steam from this line but closed to steam from the steam blower line.

There is also a pipe extension 75 connected to the tip 7 of the exhaust nozzle N, the free end 76 of which extends into the angularly disposed section 14 of the conveyor H a predetermined distance. Upon each impulse of the exhaust from the exhaust cavities O, exhaust steam is injected 50 into the angularly disposed section 14 to create 55 a partial vacuum therein. This section 14 also simultaneously receives the effect of the exhaust through the neutralizer nozzle 21 and the suction in the conveyor due to the draft in the fire box A materially assists in the disposal of the cinders 60 through the conveyor to the fire box.

While I have illustrated and described the cinder disposal device in connection with what is known as a cyclone type of arrester positioned in the smoke box of a locomotive, it is to be understood that this method of conveying cinders is not limited to any particular spark arresting device as it is applicable to various types of arresters, such as the surface or bottom types.

I have also shown the extensions extending 70 from the exhaust cavities O of the locomotive cylinders D connected to a particular portion of the cavities. This connection, however, is only incidental since locomotives vary in design and construction and these connections are therefore 75

made to the exhaust cavities where most convenient. The live steam branch connection may also be made to the steam line at the most convenient place.

5. The cinder conveyor H as illustrated is positioned along the outside of the boiler shell but due to the various types of locomotives, the location of the conveyor H varies.

10. While I have illustrated and described a preferred form of cinder disposal apparatus, changes and modifications will readily suggest themselves by those skilled in the art and I therefore aim to cover all such changes and modifications as come within the spirit and scope of the appended claims.

15. I do not restrict myself to any unessential particulars, but what I claim and desire to secure by Letters Patent is:

1. The combination with a locomotive having exhaust steam cavities, of a cinder disposal device having air inlet openings, said locomotive having a smoke box and a fire box and said cinder disposal device carrying cinders from the smoke box to the fire box and including a neutralizing member for smoothing out the pulsations in flow of exhaust steam conveyed thereto from the exhaust steam cavities, means for introducing live

steam into said neutralizing member, and means for discharging the live and exhaust steam from said neutralizing member into said conveyor tube in the form of a jet to insure a positive disposal of cinders therethrough and to cause a flow of air through said air inlet openings. 5

2. A waste product disposal device for combustion systems comprising a conveyor tube having angularly disposed arms, an intake opening in one of said arms, a discharge opening in another 10 said arm, steam injection means at said intake opening, combined steam injecting and air inducing means at the juncture of said arms, and manually controlled and pressure controlled steam admission means for said injecting means. 15

3. A combustion products disposal apparatus comprising a conveyor tube having an intake end and a discharge end, a compressed-fluid injector at said intake, another such injector spaced at a distance from said first injector and adapted to 20 induce air into said tube, manually operable means controlling the admission of compressed fluid to said second injector, and pressure responsive valves also controlling admission of compressed fluid to said second injector. 25
